CARBURETER.

1,200,039.

Specification of Letters Patent.

Patented Oct. 3, 1916.

Application filed December 26, 1911. Serial No. 667,612

To all whom it may concern:

Be it known that I, JAMES A. SPEED, a citizen of the United States, residing at San Francisco, in the county of San Francisco and State of California, have invented new and useful Improvements in Carbureters, of which the following is a specification.

With prior forms of float feed jet carbureters, the suction of the engine has been applied to a nozzle or outlet to draw fuel into a passing current of air for the purpose of mixing it therewith. In cases where means have been provided for throttling the charge of mixture to the engine, it has been found necessary to further dilute this mixture with additional air, since, if the initial air opening was sufficiently small to cause the requisite vacuum on the fuel nozzle at the minimum opening of the throttle, it would be too small to supply the engine when the throttle was fully opened, also since the vacuum in the mixing chamber would become very considerable as the throttle was opened, owing to the small air intake, and, as the fuel would flow from the nozzle substantially in proportion to the vacuum while the air would be greatly attenuated, the mixture would become too rich. It is doubtful whether an intimate mixture of maximum efficiency under all conditions of speed and load will ever be attained by a carbureter of such type.

An object of my invention is to provide a carbureter in which the throttling of the mixture is accomplished by decreasing the size of the mixing chamber.

A further object of my invention is to provide means for retarding the speed of the opening of the valve controlling the admission of air, while allowing the rapid closing of the same.

A further object of my invention is to provide a carbureter in which the opening of the throttle valve is limited as to its rapidity of operation independently of the speed at which the external controlling means may be moved.

A further object of my invention is to provide a carbureter in which is eliminated the danger of fire resulting from what is commonly known as "backfiring."

A further object of my invention is to pro-

vide a carbureter having a mixing chamber, which, unless otherwise controlled, automatically increases in conducting capacity proportionately to the suction of the engine.

In the accompanying drawing, Figure 1 is a vertical section of the carbureter; Fig. 2 is a horizontal section on the line 2—2 of Fig. 1; Fig. 3 is a detail cross section on the line 3—3 of Fig. 1; Fig. 4 is a detail side view of the controlling device for the plunger; Fig. 5 is a detail end view of the same; Fig. 6 is a detail side view of a staple.

Referring to the drawing, 1 indicates a float chamber within which is contained a float 2 of light material, as cork, suitably pivoted, as shown at 3, to regulate the admission of fluid fuel into said float chamber through the fuel inlet 4. The bottom of said float chamber has a central aperture 5, through which passes a cylindrical portion 6 of the body of the carbureter which forms the wall of a dash pot, a nut 7 being screwed upon the reduced lower end of said portion 6 and clamping the bottom of the float chamber against the shoulder 8 formed by said reduced end. Held securely by a tight fit in the wall of the dash pot is a fuel conduit 9, the enlarged lower portion of which forms the bottom of the dash pot, the channel of which conduit 9 communicates with the float chamber through registering conduits 10 formed through said fuel conduit and the cylindrical portion 6. Fitting snugly in said dash pot is a plunger 11, the top of which is, by spider arms 12, integrally connected with a valve 13. Said plunger is formed with a central vertical conduit 14 closed at the upper end. The lower portion 90 of said conduit is enlarged and closely surrounds the upper reduced portion of the fuel conduit. A conduit 60, having an inner restricted portion 61, leads from the float chamber into the bottom of the dash pot. A ball valve 62 closes the entrance to said restricted portion and prevents gasoline flowing inwardly in said conduit, although permitting it to flow rapidly outward there-through. A minute conduit 63 permits gasoline to flow inwardly past said ball.

In the bottom of the fuel conduit is screwed a screw 15, the upper end of which is split and formed with a socket, and with

inwardly extending lips 16. These lips are adapted to snap into, and engage, a groove 17 in the lower end of a tapering pin 18, and thus removably hold said pin in said socket.

5 Said pin extends upwardly in the fuel conduit, and, passing into the lower end of the conduit 14 in the plunger, limits the size of the entrance into said fuel conduit 14 to a greater or less extent dependently upon

10 the size and taper of said pin and the extent to which the screw 15 is screwed up or down within the fuel conduit. By reason of the taper in the pin 18, the size of the passage up the conduit in the plunger increases as

15 said plunger rises, which rise is caused in the manner hereinafter explained. Said conduit in the plunger connects with a plurality of vertically elongated openings 20 extending radially or transversely through said

20 plunger, four such openings being here shown, which discharge at their outer end into an annular chamber 21, formed in the outer surface of the plunger. Said chamber 21 is of considerable height, so that it is

25 adapted in every position of the plunger to communicate with a considerable number of ports 22 (Fig. 2) leading through the wall of the dash pot into an annular recess or fuel discharge chamber 23 formed in the

30 carbureter body. Said chamber or recess 23 is closed on its outer side by a wall 24, depending from the valves 13 hereinbefore described as formed integral with the plunger, and the upper side of said chamber 23

35 is formed partly by a horizontal extension 25 from the dash pot, and partly by the lower side of said valve, the bottom of said chamber being formed by a horizontal radial extension 32 from the wall 6. The outer

40 side of said valve is conical and tapers downwardly, and it is seated in a conical downwardly tapering seat 26 formed in the inner wall 27 of the carbureter body, the outer wall 28 of said carbureter body forming with

45 said inner wall a water jacket 29 having a water inlet 30 and outlet 31. The lowermost position of said valve, as determined by its outer wall being in contact with its seat, is such that the lower edge of the depending

50 wall 24 of said valve very closely approaches the horizontal, radial extension 32. In practice I have found a distance of one-thirty-second of an inch to be satisfactory. Through the dash pot are formed a suitable

55 number of air ports 33 terminating at said wall. Around the dash pot is shutter 34, having openings adapted to register with said ports and having an outwardly extending lug 35 by which, through any suitable

60 means, said shutter can be rotated to close more or less said air ports in case it is required to do so. Between the valve 13 and the dash pot is an auxiliary valve or cone 36, surrounding the dash pot, and which can

65 slide vertically thereon, and can rest upon

said horizontal portion 25, the outer wall of said cone tapering upward, and being adapted to fit within an upwardly tapering inner wall of the main valve. The upper movement of said auxiliary valve is limited by a shoulder 37 in its inner side abutting against the lower edge of a split nut 38 screwed upon the outer side of the tubular portion of the dash pot.

70 40 indicates a substantially conical or upwardly convergent cover adapted to be secured in the usual manner to the induction pipe, not shown. The lower circular edge of said cover fits upon the upper edge of the mixing chamber casing, and said cover is

75 secured thereto by means of the inwardly extending upper edge of a clamping ring 41, which is screwed on to an external thread 42 formed upon the mixing chamber casing. Said cover is formed with a horizontal box

80 through which is passed a cylindrical sleeve 43 having an eccentric bearing, and also formed at its outer end with a hexagonal head 44 to permit it to be turned in said box

85 to adjust the bearing to any position desired and thus to regulate the extent of the minimum opening for the admission of fuel mixture to the induction pipe. Through said bearing extends a shaft 45. Upon the outer end of said shaft is secured a split

90 brass sleeve 46, and around said sleeve is clamped by a screw 47 the split end of an arm 48, adapted to be connected with operative means leading to a distant point. The screw 47 through the split end of the arm

95 permits the arm to be secured thereon at any position on the sleeve. The sleeve 46 forms a shoulder upon the shaft for preventing longitudinal movement thereof and likewise

100 provides a larger bearing surface for the purpose of securing the arm against rotation on said shaft. To the inner end of said shaft 45 is rigidly secured a crank arm 49 formed of two parallel plates, between the ends of

105 which is pivoted, by a pivot-pin 50, a link

110 51, the end of which is pivoted between the ends of two parallel arms 52 pivoted upon a lug 53 formed on the inner surface of the cover. Said link has an upward extension

115 54 past its pivotal union with the crank arm, to provide means for arresting it in the lowest position, which means comprise also a staple 55 passed through holes in said crank arm, which staple is normally retained in position by means of an upwardly

120 bent extension 56 of the pivot pin 50 which pivotally connects the crank arm to the link. By turning said pivot pin so that said extension 56 is out of the way of said staple, said staple can be removed and its position

125 changed. Said staple is formed with one arm 57 longer than the other, so that, when said staple is removed and turned half way around and replaced in position, and also

130 the extension 54 of the link is placed upon

the other side of the crank arm, the movement of the link is on the opposite side of the shaft to that on which it was formerly. The object of providing this alternative arrangement is to enable the device to be used with a link or other mechanism which is either pushed toward the device, or pulled from it.

It will be observed that there is no direct connection between the lower end of the link and the valve 13, so that said link and the parts connected thereto do not constitute means for lifting the valve, but only means for arresting the valve in its upward movement, and for determining the extent beyond which it cannot open. The valve operates automatically by the suction of the engine, the function of the link and the parts coöperating therewith being merely to provide means for closing and for limiting, when desired, and to any extent desired, the movement of said valve.

The following is believed to be the mode of operation of the carbureter:—The first effect of the starting of the engine is to raise the auxiliary valve 36 (which is comparatively light) and thus, unless the split nut has been screwed too far down, to close the annular passage 58 between said auxiliary and main valve. Immediately thereafter the main valve 13 is drawn up by the suction of the engine, opening the passage 59 between said main valve and its seat. The gasoline contained within the slotted openings 20, annular chamber 21, and connecting ports 22, and annular chamber 23, is drawn out therefrom through ports 19 in said depending wall 25 and upwardly in said passage 59 and at the same time air is drawn through the ports 33 and beneath the lower edge of the depending wall 24, and, as the main valve is lifted higher by the suction of the engine, the opening between the lower edge of the wall and the extended portion 32 of the dash pot is increased, and consequently more air is admitted to mix with the gasoline. Part of the mixture also escapes from the annular chamber 23, by the conical passage 58 between the auxiliary and main valves. These passages 58, 59, are increased in size as the lift of the valve increases.

The chief purpose of the auxiliary valve 36 is to prevent danger from back-firing. For the first effect of back-firing is to force both valves to their lowest position, and the annular conical passage 58, which is open when both valves are in their lowest positions, this furnishes a vent for the gases, in case of back-firing of the engine, and permits said gases to escape through the air ports 33 into the atmosphere, while entirely preventing the passage of flame to the fuel chamber 23, owing to the narrowness of the opening and the cooling effect of the walls.

I have herein, for the sake of brevity,

spoken of the liquid fuel being gasoline, but it is evident that any other suitable fuel may be used with my invention.

An important feature of my invention consists in the construction of the mixing chamber, by which term I mean to include those portions of the carbureter above the level at which the incoming current of air meets the gasoline, principally the two annular conical passages 58, 59, as far as to the upper ends of said passages. The annular conical passages 58, 59, constitute the mixing chamber of my improved carbureter, for although the inflowing current of air meets the gasoline somewhat below the lower ends of said passages yet the mixing effect produced below said passages is very small, and may be neglected. This mixing effect is caused by the friction of the gases with the walls of said passages, which is considerable, because said passages, even when opened to their fullest extent, are not more than $\frac{1}{8}$ of an inch in width for an inch and a half carbureter. This frictional resistance to the flow of the gases tends to repeatedly reflect said gases from their straightforward direction and thus causes them to commingle with each other, to insure which effect being produced I may sometimes form the walls of these passages with horizontal circular grooves. One feature of my invention which I believe to be novel, and which is of extreme importance, is that these passages 58, 59, which constitute practically the entire mixing chamber, continually increase in transverse size, unless otherwise controlled, as the suction is increased, because the pairs of parallel walls by which these passages are formed are oblique to the direction of movement of said movable walls. Consequently, as said movable walls move upward, while still remaining parallel with the stationary walls, they separate therefrom and the passages increase in transverse size, in proportion as said upward movement increases. Now this feature of my invention differs from prior constructions in that, in said prior constructions, so far as I am aware, it was only the inlet or outlet openings of said passages that were increased or diminished in size to vary the supply of mixture. The passages themselves were not so increased or diminished. Such prior constructions, therefore, resulted in lack of uniformity in the speed of the mixture, said mixture passing said inlets or outlets at a high speed, and, after or before making the passage, moving at a comparatively slow speed. This had the effect of producing condensation of the gasoline vapor, technically known as "loading" of the carbureter, on arriving at the enlarged portions of said passages, and in which their velocity was greatly reduced, and this effect was espe-

cially noticeable when running the engine at low speeds. Now it will be observed that with my construction these passages 58, 59, which, as before stated, constitute the mixing chamber, are at all times smaller than the entrance to said passages, which is just the opposite to the prior constructions. Consequently there can be no condensation of the gasoline vapor due to checking of the speed. I am thus the first, so far as I am aware, to provide a mixing chamber which increases in transverse size automatically with the suction of the engine and which is therefore so constructed as to permit a substantially uniform speed of the gases at all times.

A further important feature of my invention consists in the very accurate and automatic proportioning at all times of the gasoline to the amount of air admitted, so that the mixture is of substantially uniform quality, as well as of quantity exactly that required for the supply to the engine. This is occasioned by the fact that it is the current of air only, greater or less according to the degree of suction of the engine, which induces a supply of gasoline. Consequently, if the engine slows down, as under heavy load, so that the suction produced thereby decreases, and the plunger or valve drops, and the induced current of air also decreases, then simultaneously therewith there will be a reduction in the amount of gasoline vapor carried by said current of air into the passages 58, 59, constituting the mixing chamber, which passages also correspondingly decrease in size, thus maintaining the velocity of the mixture approximately constant.

A very important feature of my invention is the employment of a dash-pot to limit the speed of opening of the throttle valve independently of the speed at which the external controlling means may be moved. This dash-pot also limits the speed of opening of the air valve, which is integral with the throttle valve. When a vacuum is applied above valve 13, said valve is raised by the pressure of the air and gasoline vapor flowing against its under surface. If this valve be suddenly opened, there is a tendency, during the period of opening, for the mixture to become weak in gasoline vapor, partly because the air is already gaseous while the gasoline has to be gasified, and partly because the speed of the air tends to increase more rapidly than that of the gasoline, owing to the greater inertia of the liquid. This temporary impoverishment of the mixture is very noticeable in many types of carbureters. By limiting the speed of opening of the throttle valve by means of the counter-suction produced in the dash-pot by the lifting of the plunger integral with this

valve, time is allowed for the gasification of the requisite amount of gasoline to keep the mixture of substantially constant proportions; and the equally slow opening of the air valve is also of assistance in producing this result.

An important feature of the invention is that no air can obtain access to the bearing of the plunger within the cylindrical wall of the dash pot either above or below the vapor chamber. The consequence is that the inner wall of the dash pot is, at all times, and throughout its entire length, lubricated with gasoline, either working up from the dash pot, or condensed from the gasoline vapor in the vapor chamber. The result is that the plunger moves very sensitively to variations in suction of the engine, and thus also the supply of mixture is very accurately proportioned to that required for operating the engine. Moreover the wearing of the parts is very slight. It will thus be clear that the dash pot and its plunger exercise control of the valve permitting its rapid descent but slow ascent and therefore permitting a quick reduction while compelling a slower increase in the volume of the mixing chamber.

In addition to the improvements enumerated above, there are others incorporated in my carbureter, which however, are made the subject of a separate application by me—Serial No. 610,343, filed February 23rd, 1911, to which attention is directed, and which was issued as U. S. Letters Patent 1,145,172 on July 6th, 1915, and also to my co-pending application Serial 861,520 filed Sept. 14, 1914.

I claim—

1. A carbureter formed with a vapor chamber, a gasoline conduit discharging into said chamber, means for conducting air to mix with fuel in the outer part of said chamber, said carbureter being formed with a conical wall above said chamber, and a movable element adapted to be moved by the suction of the engine and having a conical wall substantially parallel with the first named wall, the lower end of the annular space between said walls being connected with said chamber.

2. A carbureter formed with a vapor chamber, a gasoline conduit discharging into said chamber, means for conducting air to mix with fuel in the outer part of said chamber, said carbureter being formed with a conical wall above said chamber and coaxial therewith, and a movable element adapted to be moved by the suction of the engine and having a conical wall substantially parallel with the first named wall, the lower end of the annular space between said walls being connected with said chamber.

3. A carbureter formed with a vapor chamber and provided with a gasoline cou-

- duit discharging into said chamber, means for admitting air to portions of said chamber remote from said conduit, said carbureter being provided with stationary and 5 movable parts arranged to provide a mixing chamber therebetween, said mixing chamber being connected with the outer portions of said chamber to draw off the gases therefrom, the movable part being adapted to be moved by the suction of the engine to enlarge said mixing chamber.
4. A carbureter formed with a vapor chamber and provided with gasoline conduit discharging into said chamber, means 15 for admitting air to said chamber at points remote from said conduit, a movable element adapted to be raised by the suction of the engine, said element and the carbureter having each a plurality of walls forming together 20 a plurality of annular passages, said passages communicating at their lower ends with the chamber to form mixing chamber sections, said sections increasing in transverse size as said element is raised.
5. A carbureter formed with a vapor chamber and provided with a gasoline conduit discharging into said chamber, means 25 for admitting air at parts remote from said conduit, a movable element adapted to be moved by the suction of the engine, said element and the carbureter having walls forming a narrow annular passage, said passage increasing in transverse size when said element is so moved.
6. A carbureter having a vapor chamber, means for supplying liquid gasoline thereto, a device adapted to be moved by the suction of the engine, said device forming with a 35 wall of the carbureter a mixing chamber 40 communicating with said chamber, means for conducting air to said fuel discharge chamber, at a point remote from the entrance thereinto of liquid gasoline, and means for preventing a rapid movement of 45 said device when the suction of the engine is applied thereto to enlarge said mixing chamber, while permitting a rapid movement in the other direction.
7. A carbureter having a vapor chamber, 50 means for supplying liquid gasoline thereto, a device forming with a wall of the carbureter a mixing chamber communicating with said chamber, means for conducting air to said fuel discharge chamber at a point
- remote from the entrance thereinto of liquid 55 gasoline, said carbureter being formed with a dash pot having a communication with the liquid supply of gasoline and said device having a part movable in said dash pot, and a valve in said dash pot preventing the too 60 rapid movement of said liquid gasoline into the dash pot when said device is moved by the suction of the engine but permitting its rapid movement therefrom.
8. A carbureter having a vapor chamber 65 and means for conducting gasoline into said chamber, means for conducting air into said chamber at a point remote from the gasoline entrance, a movable element arranged to be moved by the suction of the engine and 70 forming, with stationary portions of the carbureter, a mixing chamber into which gasoline vapor and air are adapted to be drawn by said suction, said fuel discharge chamber being formed with a restricted passage 75 between the parts at which the gasoline and air enter.
9. A carbureter having a float chamber and a float therein, and formed with a vapor chamber, a gasoline conduit conducting 80 liquid gasoline to said chamber, means for conducting air to the outer portions of said chamber, a movable device adapted to be moved by the suction of the engine and 85 forming with stationary portions of the carbureter a mixing chamber leading from said chamber, the outlet of said conduit into said fuel discharge chamber being higher than the level of the gasoline in the float chamber as determined by the float therein. 90
10. A carbureter having a vapor chamber, means for conducting gasoline into said chamber, means for conducting air to the outer portions of said chamber, a movable element adapted to be moved by the suction 95 of the engine, said movable element and carbureter having walls forming a mixing chamber leading from the fuel discharge chamber, the carbureter being formed with a dash pot and said element having a plunger in said dash pot.
